U.S. Cl. D34—5 F

FIG. 1

FIG. 2

FIG. 3

FIG. 4

FIG. 5

FIG. 6

FIG. 1 is a top view of a pool showing my design;
FIG. 2 is a right side view of said pool;
FIG. 3 is a front view of said pool;
FIG. 4 is a rear view of said pool;
FIG. 5 is a bottom view of said pool; and
FIG. 6 is a sectional view taken substantially along the line 6—6 of FIG. 1.
Since the pool is symmetrical, the left side view thereof is the same as the right side view.

I claim:
The ornamental design for a pool, substantially as shown and described.
